UNITED STATES PATENT OFFICE

JAY ACKERMAN, OF NEW YORK, N. Y., ASSIGNOR TO THE CHASE COMPANIES, INCORPORATED, OF WATERBURY, CONNECTICUT, A CORPORATION

DESIGN FOR A COMBINED TRAY AND RECEPTACLES FOR SMOKERS

Application filed October 7, 1932. Serial No. 45,251. Term of patent 3½ years.

To all whom it may concern:

Be it known that I, JAY ACKERMAN, a citizen of the United States, residing at New York, in the county of New York and State of New York, have invented a new, original, and ornamental Design for a Combined Tray and Receptacles for Smokers, of which the following is a specification, reference being had to the accompanying drawing, forming part thereof.

The figure is a perspective view of a combined tray and receptacles for smokers showing my new design.

The receptacles and tray remain intact and are intended to be sold as a unitary article.

I claim:

The ornamental design for a combined tray and receptacles for smokers as shown and described.

JAY ACKERMAN.
